SUPPORT FOR TRACTOR OR THE LIKE

Clovis O. Drake, 846 44th St. NW., Canton, Ohio, and
Russell S. Drake, 3244 Twin Hills Road, Uniontown,
Ohio

Filed Feb. 29, 1960, Ser. No. 59,570

Term of patent 14 years

(Cl. D41—1)

FIG. 1 is a front elevation of a support for tractors or the like showing our new design;

FIG. 2 is a side elevation thereof;

FIG. 3 is a top plan view thereof;

FIG. 4 is a bottom plan view thereof;

FIG. 5 is a reduced side elevation thereof with the broken-line representation of a garden tractor being shown for illustrative purposes only; and

FIG. 6 is an enlarged fragmentary cross-sectional view of the knob taken on line 6—6 of FIG. 2.

We claim:

The ornamental design for a support for tractors or the like, substantially as shown and described.
